[57] CLAIM

The ornamental design for a sanding machine for dry lining, as shown and described.

DESCRIPTION

FIG. 1 is a front elevational view of the sanding machine for dry lining showing my new design;

FIG. 2 is a rear elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken line showing of a vacuum machine is for illustrative purposes only and forms no part of the claimed design.

The pair of wavy-lines shown on the power cord indicates that the cord may be of varying length.
